Specification for Design.

Patented Aug. 10, 1920.

Application filed May 20, 1920. Serial No. 382,990. Term of patent 14 years.

To all whom it may concern:

Be it known that we, FRANCIS G. HINEGARDNER and DAVID W. BOWMAN, citizens of the United States, residing at Toledo, in the county of Tama and State of Iowa, have invented a new, original, and ornamental Design for a Sleigh-Knee, of which the following is a specification, reference being had to the accompanying drawing, forming part thereof.

In the drawing, Figure 1 is a front view

of the sleigh knee showing our new design. Fig. 2 is a plan view, and Fig. 3 is an end view also showing our new design.

We claim:

The ornamental design for a sleigh knee, as shown.

In testimony whereof we affix our signatures.

FRANCIS G. HINEGARDNER.
DAVID W. BOWMAN.
